UNITED STATES PATENT OFFICE.

FRED C. EHINGER, OF PALMYRA, MICHIGAN.

HANDLE FOR TOOLS OR THE LIKE.

1,192,177.

Specification of Letters Patent. Patented July 25, 1916.

Application filed May 29, 1915. Serial No. 31,242.

To all whom it may concern:

Be it known that I, FRED C. EHINGER, a citizen of the United States of America, residing at Palmyra, in the county of Lenawee and State of Michigan, have invented certain new and useful Improvements in handles for Tools or the like, of which the following is a specification, reference being had therein to the accompanying drawings.

My invention relates to handles for tools or the like, and resides in the novel connection between the ferrule and the handle proper, and further in the novel method of attaching the ferrule to the handle proper.

In the drawings,—Figure 1 is a perspective view of the handle embodying the invention; Fig. 2 is a central, longitudinal cross-section therethrough; Figs. 3 and 4 are side elevations of the handle proper and the ferrule respectively; and Figs. 5 and 6 illustrate the manner of assembling the parts.

In handles for tools or the like, it is not only desirable to have the ferrule so connected to the handle as to prevent the ferrule from working loose, but it is also necessary, or a practical handle, that the ferrule prevent splitting of the handle neck when the head of the tool is driven into the end of the handle. With my invention the ferrule is firmly attached to the handle proper against disengagement, and also there is provided a suitable reinforcement for the neck of the handle, which tends to prevent splitting thereof.

Generally speaking, my improved method consists in forming the handle proper with a band of compressible, expandable material, and forming the ferrule with a nonexpansile socket which is of larger cross-section than the cross-section of the band of the ferrule that fits the neck of the handle proper, and then forcing the head into engagement with the socket. During the engagement the head of the handle will be impressed, but when it passes into engagement with the socket it will be expanded. Therefore, after the ferrule is in place upon the handle it will be tightly secured thereto. Referring to the structure shown in the drawings, A designates the body of the handle proper, C the neck thereof and D is the ferrule. The ferrule D preferably is formed of a seamless metal structure having a band portion E for fitting the neck of the handle and provided with a socket portion of greater cross-section than the cross-

section of the band at the junction between the latter and the socket. Preferably the neck portion of the handle tapers toward the head, while the head has a transversely rounded periphery. This spherical-like head provides a tapering face H, the purpose of which will more fully hereinafter appear. The socket of the ferrule is of a configuration similar to the configuration of the head and the handle proper, except the end is provided with an aperture I to permit the tang of the tool to be driven into the handle.

Preferably the neck portion is formed of sufficiently less cross-section than the body portion, to place the outer faces of the body portion and the ferrule at the junction thereof in the same plane. This provides a shoulder J against which the end of the ferrule tightly abuts when the parts are assembled.

The ferrule D is formed of comparatively heavy gage metal and therefore is non-expansile, but the head which is solid, is made of compressible, expandable material—preferably by making the handle proper of soft wood, as for instance basswood.

To assemble the parts the ferrule is forced onto the handle proper, and during this engagement the face H cooperates with the tapering band to compress the head sufficiently to allow it to pass through the smaller end of the band portion of the ferrule into engagement with the socket F. When the head of the handle proper passes into engagement with the socket portion it expands and fills, or substantially fills the socket portion. As the socket portion, at its junction with the band, flares outwardly rather abruptly, when once the head has passed into engagement with the socket portion it will be retained therein. When the tang of the tool, such as a file, is driven into the inner end of the handle, it will tend to further increase the size of the head, thereby more securely lodging the ferrule in place.

Preferably the end of the handle proper is provided with a bore for receiving the tang of the tool, but the head is not split and to this extent may be considered solid.

While I have shown and described an exceedingly desirable form of the invention, I do not wish to limit the protection to the particular structure shown, nor to the exact method described.

What I claim as my invention is:—

1. In a handle for tools or the like, the combination of a handle proper having a

tapering neck portion and having a head at the small end of the tapering neck portion of greater diameter than the latter at the junction between the head and the neck,
5 said head having a transversely-rounded peripheral portion, and a seamless ferrule formed of comparatively heavy gage metal whereby the ferrule is non-expansible, said ferrule being provided with a tapering band
10 portion fitting the tapering neck of the handle proper and having an enlarged socket portion of greater diameter than the band at the junction between the latter and the socket, said socket being shaped to fit the
15 head and having an opening in its forward end, and the handle being made of soft wood whereby the head is compressible and expandible, said head being compressed by said tapering band portion during the engaging movement of the ferrule upon the handle proper and expanding at the completion of said movement.

2. The method of forming handles for tools, comprising forming a handle proper with a neck portion terminating at its inner end in an enlarged solid head of compressible expandible material and forming a seamless non-expansible ferrule having a band portion of a size to fit the neck portion of the handle proper, and having a socket portion at one end thereof of a size to fit the head, said socket being of considerably greater diameter than the band at the junction between the latter and the socket, and
30

in then assembling the ferrule and handle by 3 forcing the head through the band portion into engagement with the enlarged socket, the head being compressed by said band portion during the forcing operation and expanding at the completion of said opera- 4
tion.

3. The method of forming handles for tools, comprising forming a handle proper with a tapering neck portion terminating at its inner end in an enlarged solid head of 4 compressible expandible material and forming a seamless, non-expansible ferrule having a tapering band portion of a size to fit the neck portion of the handle proper, and having a socket portion at one end thereof 5 of a size to fit the head, said socket being of considerably greater diameter than the band at the junction between the latter and the socket, and in then assembling the ferrule and handle by forcing the head through the 5 band portion into engagement with the enlarged socket, said head being compressed by said band portion during the forcing operation and expanding at the completion 6 of said operation.

In testimony whereof I affix my signature in presence of two witnesses.

FRED C. EHINGER.
